UPHOLSTERY FORMING MACHINE

Clarence W. Avery, Detroit, Mich., assignor to
The Murray Corporation of America, a corporation of Delaware

Application January 13, 1936, Serial No. 58,859

5 Claims. (Cl. 112—2)

This invention relates to apparatus for, and a method of, preparing upholstery trim for use in connection with the manufacture of automobile seat constructions.

More particularly the present invention relates to a novel method of distributing a uniform layer of padding material upon a backing sheet, dividing the material along substantially parallel longitudinal lines to provide a tufted effect, covering the padding material with a suitable finish trim, forming the trim material to a contour substantially that desired in the finished article and stitching the finish material in position to the backing sheet, thus firmly securing isolated bodies of the padding material in position between the finish material and backing sheet.

It is a general object of the present invention to provide a machine which will substantially automatically, and continuously form a series of padded upholstery trim sections, which each comprise a pair of layers of fabric material with relatively isolated sections of padding material secured in position therebetween.

Yet another object of the present invention consists in the provision of apparatus for accurately and efficiently separating a substantially homogeneous relatively thick layer of padding material into isolated sections which constitute tufts in the finished product.

Yet another object of the present invention consists in the provision of apparatus which is so constructed and arranged that it will operate substantially continuously, to produce finished padded trim panels of substantially uniform composition and construction, and in which the padding material is securely fastened in place and has been preformed to provide a predetermined desired tufted effect.

Many other and further objects and advantages of the present invention will become apparent from the following specification when considered in connection with the accompanying drawing forming a part thereof.

In the drawing:

Fig. 1 is a perspective view of the complete machine, showing in detail the relative position of the various parts and the manner in which they are co-related.

Fig. 2 is an enlarged fragmentary perspective view of one of the caterpillar chains which serve to form the separated sections of padding material to the predetermined desired form and curvature, and which serve the purpose of retaining the padding material and finish trim in position during the stitching operation.

Fig. 3 is a sectional perspective view of a conventional automobile seat, illustrating the improved finish trim panel applied thereto.

Fig. 4 is a fragmentary perspective view, illustrating in detail the stitching mechanism and the manner in which the finished trim panel is retained in position during the stitching operation.

Fig. 5 is a sectional view taken substantially on the line 5—5 of Fig. 3, illustrating the finished upholstery trim panel.

Fig. 6 is an enlarged fragmentary perspective view, illustrating in detail the mechanism which serves to grip the marginal edge of the backing sheet as it travels through the machine in order to maintain this sheet under the proper tension and position the same properly with respect to the frame work of the machine along which it travels.

Fig. 7 is an enlarged fragmentary perspective view of the cutter knives, which serves to divide the padding material into the predetermined sections.

Fig. 8 is an enlarged fragmentary perspective view of a modified form of apparatus for dividing the layer of padding material into predetermined sections.

With more particular reference to the drawing, the apparatus in general comprises a work table 10 of substantial length and of a width sufficiently wide to accommodate the width of the upholstery trim panels which it is desired to produce. Mounted in stationary position with respect to the work table 10, at one end thereof, is a frame work 11, which serves to support a reel 12 of burlap 13 or other suitable backing material. This burlap web 13 is fed from the reel 12 by means of a pair of feed rolls 14 and passes over an idle roller 15, the upper surface of which lies substantially in the plane of the upper surface of the table 10.

The web 13 is fed longitudinally along the table and at the rear end of the table are provided a pair of sprocket pulleys 18, around which are fed caterpillar chains 19, each composed of gripping links 20, which are of a construction adapted to grip the lateral marginal edges of the backing web 13 and maintain this web properly tensioned throughout the entire longitudinal length of the work table while the various operations are being performed upon the web.

While it will be apparent that any suitable means may be utilized for the purpose of gripping the lateral edges of the backing web 13, I have shown by way of illustration the caterpillar chain 19, in which the links 20 comprise lower jaws 22 with pivotally mounted substantially vertically disposed upper jaws 23. Each

of the jaws 23 is provided with an upwardly extending latch 24, preferably formed integrally therewith, which engages a cam plate 25, mounted in stationary position on the table 10. As is clearly seen in Fig. 6, the cam plate 25 serves to move the jaw member 23 inwardly with respect to the jaw member 22 at about the time the marginal edge of the backing web 13 enters between the jaws. This cam 25 serves to retain these jaws in open position until the marginal edge of the backing web has entered the full depth between the jaws and then the latch 24 will slide forwardly past the front end of the cam surface and allow the jaws to swing by force of gravity, down into engagement with the backing sheet 13, thus firmly securing this sheet between the jaws 23 and 22. It will be appreciated by reference to Fig. 6 that the jaws are of such construction that subjection of the backing sheet to lateral tension serves merely to tighten the grip of the jaws 22 and 23 on the marginal edge of the backing sheet.

As has been pointed out above, these caterpillar chains 19 preferably extend throughout the entire longitudinal length of the table and it will be appreciated therefore that the backing web of burlap 13 is gripped in its marginal edges and maintained under proper tension and accurately in position throughout the entire length of the table and consequently throughout the entire period when the various forming and treating operations are performed on the backing sheet.

Means are provided for distributing a substantially homogeneous uniform layer of non-woven fibrous padding material upon the backing web 13. While any suitable means may be used for accomplishing the results desired in this connection, I have shown by way of illustration one preferred method and apparatus for accomplishing this result. The apparatus disclosed generally comprises a Garnetting machine 30, into which a suitable supply of non-woven fibrous material may be fed. As is conventional in apparatus of this general type, the cutters and combs of this Garnetting machine serve to tear up the fibers and distribute them at random substantially in a uniform non-woven layer as they are fed out of the machine by means of an endless conveyor belt 31 operating upon a pair of pulleys or rollers 32. This web of padding material, designated as 33, is fed from the conveyor belt 31 to an oscillating conveyor belt 35. The conveyor belt 35 is mounted upon a pair of rollers 36, which are journaled for rotation in a frame work 37 which is pivoted to the frame work carrying the conveyor belt 31. The lower end of the frame work 37 is provided with a pair of brackets 40 which have journaled thereon a plurality of rollers 41 which serve to engage a pair of transversely extending trackways 44 extending throughout the entire transverse width of the work table 10. Suitable sprocket chains 45 serve to drive not only the conveyor belt 35 but also serve the purpose of reciprocating the frame work 37 transversely with respect to the work table 10 in order that the layer of non-woven padding material will be distributed substantially uniformly on the backing web 13 which passes longitudinally along the table. It will be appreciated that the reciprocation of the frame work 37 is relatively rapid with respect to the longitudinal movement of the backing web 13 and consequently a relatively heavy, uniform, substantially homogeneous layer of non-woven padding material will be uniformly dis-

tributed upon the surface of the backing sheet 13.

While the padding material generally used for constructions of this general kind is of such a nature that it is not necessary to adhesively secure it to the backing web, if desired the web as a whole may be covered with a film of liquid adhesive prior to the application of the padding material and the padding material may be compacted into engagement with the backing web after the fibrous material has been distributed thereon substantially in the manner described in detail in applicant's prior co-pending application, Serial No. 54,121, filed December 12, 1935, and assigned to the assignee of the present invention.

In order that the padding material, which after distribution by the conveyor system described above lies in substantially a layer of uniform thickness, may be divided, means are provided for separating the padding material along substantially uniformly spaced parallel longitudinal lines. While various means may be employed for accomplishing this general result, by way of illustration I have shown a method which has been found particularly satisfactory for this purpose.

While it may be appreciated that a pair of co-operating rollers, one of which has a groove to receive the other, may be utilized for the purpose of separating the matted layer of fibrous material into relatively isolated strips, the present application discloses the use of toothed rotary knives for accomplishing this purpose.

A rotary shaft 50 is mounted in suitable bearings and extends transversely of the framework. Means, not shown, are provided preferably for driving the shaft at relatively high speed. A plurality of rotary knives 51 are secured to the shaft 50 for rotation therewith and it will be appreciated that these knives may be spaced one from another in accordance with the width of the tuft desired to be produced upon the finished upholstery trim panel. Inasmuch as the padding material is very tough, and it is highly desirable that the segregated areas be separated slightly one from another, means are preferably provided to oscillate the shaft 50 in a direction transverse of the travel of the burlap backing sheet and preferably axially of the axis of rotation of the shaft 50. While any suitable means may be utilized for the purpose of accomplishing this transverse oscillation, I have illustrated by way of example an electric motor 53 mounted upon a suitable support in the frame work 10 of the table, which serves to oscillate a pivoted link 54, which is in engagement with the end of the shaft 50. It will be appreciated that as the shaft 50 is rotated at relatively high speed, and oscillated longitudinally of its axis, the layer of padding material will be severed by the rotary knives 51 and divided into parallel isolated areas, which are slightly separated one from the other, and lie longitudinally along the backing web 13. It has been found preferably to form the teeth on the knives or cutters 51 of involute form, in order that the action thereof upon the padding material will be a cutting rather than a tearing action, and the involute tooth structure of these knives has been found particularly desirable inasmuch as it effectively serves to prevent an accumulation of fibrous material in the teeth of knives and a consequent clogging thereof, thus preventing an impairment of their cutting action.

After the padding material has been divided by the knives 51 into a plurality of parallel sec-

tions, sections of fabric finish material 60 are placed upon the padding material and it will be seen by reference to Fig. 1 that the transverse width of these finish sheets must be substantially greater than the width of the webbing backing sheets 13. This is necessary inasmuch as the backing sheet is maintained in tensioned position and the surface finish layer of fabric must be shaped to conform to the padding material and consequently as it is so shaped there is a substantial reduction in the effective width thereof.

Suitable means are provided for forcing the finish trim material down in between the strips of padding material lying on the backing sheets. While this may be accomplished in any suitable manner, I have illustrated in Fig. 1 a preferred method of accomplishing this result, which has been found particularly effective. A plurality of transverse shafts 65 are journaled in the frame work 10 and extend transversely thereof. These shafts have mounted thereon rollers 66, which serve to engage the surface of the finish material and force it down between the strips of padding material. It will be appreciated that the spacing of these rollers is substantially identical with the spacing of the cutters 51 described above and consequently as the finish fabric material is engaged by these rollers, the rollers serve to force the fabric material down in between the separated strips of padding material and satisfactorily tension this material over the surface of the tufts to provide a neat, attractive, uniform finish to the upholstery panel as a whole. It is noted that the rearward shaft 65 carries three rollers which are adapted to engage the central portion of the finish material in order that this material may be gradually drawn laterally inward to assume the conformation of the padding material and to permit the desired gathering of the material and yet maintain the finished material at proper tension. The forward shaft 65 contains additional rollers which serve to force further portions of the finish material down in between the strips of padding until the forwardmost shaft 65 has a set of rollers equal in number to the set of knives for separating the padding material and consequently it will be seen that as the backing sheet as a whole passes out from underneath this gang of rollers, the finish fabric material has been formed to the curvature of the strips of padding material over which it has been tensioned.

In order to retain the finish fabric material in position with respect to the backing sheet during the stitching operation hereinafter described, a suitable frame work 70 is provided which serves to carry a plurality of endless caterpillar chains 71, each comprising a plurality of links 72 having a concave surface of semi-cylindrical curvature adapted to engage the surface of a tuft in the upholstery trim panel in order to firmly position the fabric surfaces trim in position with respect to the padding and backing sheet during the stitching operation hereinafter described. As is clearly illustrated in Fig. 4 of the drawing, these caterpillar chains serve to form the padding material to the desired rounded curvature and serve accurately to retain this padding material and fabric finish in accurate position with respect to the backing sheets during the stitching operation.

A plurality of sewing machines, comprising a guide bar 74, a vertically reciprocable sewing head 75, and a needle 76 serve to stitch the fabric finish material 60 to the backing sheets 13 along longitudinal lines in the spaces between the strips

of padding 33. The caterpillar chains 71 serve to form the padding material to the desired rounded curvature and it will be appreciated that as the web emerges from the forward end of the table, the upholstery trim panel will be substantially completely formed and all that is necessary is to cut off the backing web adjacent the terminal edges of the finish sections which have been secured thereto.

It has been found that the above described apparatus and method provides an extremely satisfactory rapid and efficient means for constructing upholstery trim panels and that the trim panels produced thereby are of exceedingly attractive uniform and satisfactory construction, being particularly neat in appearance and having the padding material firmly secured therein and uniformly distributed.

While as has been stated above, the rotary involute cutter knives 51 provide an extremely satisfactory means for separating the padding material into relatively long isolated longitudinal strips, I have illustrated in Figure 8 by way of modification a modified means by which the padding material may be separated into the desired longitudinal strips. In this form of the invention, the padding material 80 is fed through the machine and underneath a plurality of belt members 81, which engage both the upper and lower side of the padding web. It will be noted that two of these belt members 82 and 83 engage each of the strips of padding material and it is appreciated by reference to Fig. 8 that each of these belts extends at an inclined angle to the longitudinal direction of movement of the padding sheet as a whole. The divergence of these belt assemblies serves to tear the padding upon substantially parallel longitudinal lines and serves also to form the torn longitudinally extending strips into substantially the desired conformation for use in upholstery finish panels.

It will be appreciated that the form of the invention described above is merely illustrative of the generic inventive concept presented and that further modifications, substitutions and changes may be made therein without departing from the spirit of the invention, the scope of which is commensurate with the appended claims.

What is claimed is:

1. The method of preparing upholstery, which comprises applying a substantially uniform layer of padding material to a backing sheet, dividing the padding material along substantially parallel lines to form strips of padding material while supported on said backing sheet; subsequently covering said padding material with a fabric finish material, forcing the fabric material downwardly between said strips of padding material and retaining said fabric material in position while vertically stitching said finish material to said backing sheets.

2. The method of preparing upholstery, which comprises applying a substantially uniform layer of padding material to a backing sheet, dividing the padding material along substantially parallel longitudinal lines to form strips of padding material while supported on said backing sheet, subsequently covering said padding material with a fabric finish material, forcing said fabric material downwardly between said strips of padding material in the central portion of said backing sheets, and successively forcing said finish material downwardly between said strips, said forcing progressing laterally outwardly from the center of said backing sheets, and subsequently vertical-

- ly stitching said finish material to said backing sheets.
3. The method of preparing upholstery, which comprises applying a substantially uniform layer of padding material to a backing sheet, dividing the padding material into strips of padding material along substantially longitudinal lines while supported on said backing sheet, subsequently covering said padding material with a fabric finish material, forcing said fabric finish material between the strips of padding material in the central portion of said backing sheets, successively forcing said fabric finish material between said strips laterally outward from the central portion of said backing sheets, the while retaining said fabric material between the strips in the central portion of the sheets, and vertically stitching said finish material to said backing sheet between said strips.
4. A machine for forming upholstery of the type including a backing webb, padding material, and a fabric finish webb, including, in combination, a work table, means for moving a backing webb along said work table, means for distributing a substantially uniform layer of padding material on said backing webb, means for severing said padding material along longitudinal lines to form a plurality of strips of padding material while the same is supported on said backing webb, means for feeding a section of the fabric material onto said separated strips, means adapted to engage said fabric finish material serving to conform said material to the curvature of said strips, and means for vertically stitching said finish material to said backing webb between said strips.
5. A machine for forming upholstery of the type including a backing webb, padding material and a fabric finish web, a work table, means for moving a backing webb along said work table, means for distributing a substantially uniform layer of padding material on said backing webb, means for severing said padding material along substantially parallel longitudinal lines to form a plurality of strips of padding material while the same are supported on said backing web, and means including a series of spaced rollers for forming a sheet of finish material to the conformation of said strips of padding material.

CLARENCE W. AVERY. 25
